INDOOR GAME

Harter S. Hoover, Rocky River, Ohio

Application May 21, 1942, Serial No. 443,985

1 Claim. (Cl. 273—95)

This invention is in the field of games of skill usually played indoors, and is intended to be played with golf balls and a putter, or other suitable ball and striking element, for one or more people, the object being to place the ball into a specific series of receptacles in accordance with the rules and regulations of whatever game is being played. The mechanical features of my invention are particularly arranged to enable the players to change from one game to another by simple movements of certain parts, thereby simulating one or another game, such as golf, and so on.

Further objects and purposes of my invention include a simple, compact, durable and inexpensive mechanical construction, easily packed to be put away when not in use, readily, simple and quickly set up for playing. Another object is to provide such a game as can be made from any of several suitable materials and thus particularly adapted to be constructed from those not required for war purposes. Other purposes and objects of my invention will be apparent to those familiar with this art and may develop in use.

It will be appreciated that the following description and the drawings to which it relates are illustrative rather than limiting, and that various suitable and convenient modifications and changes in detail may be made without departing from the principles of my invention.

In the accompanying drawings:

Fig. 1 is a perspective showing my game set up for playing;

Fig. 2 is a developed interior detail of one cup, showing certain marking features;

Fig. 3 is a series of marking details which may be considered as several cup interiors developed, showing possible combinations for different games to be played with my apparatus;

Fig. 4 is a longitudinal vertical section on line 4—4 of Fig. 6, in the direction of the arrows, but including certain interior features not necessarily included in the form for Figs. 1 and 6;

Fig. 5 is a transverse section perpendicular to the surface of the game board, as indicated by line and arrows 5—5 of Fig. 4;

Fig. 6 is a plan view of the game, on a plane inclined to the floor; and

Fig. 7 is a view corresponding to Fig. 6 but with the catch board removed so as to show the optional ball return and signal mechanism.

My game apparatus comprises a box which is set up in an inclined position on the floor for playing, as shown in Fig. 1. A top or "catch board" 1, sunk below the upper edges of the sides

2 carries a series of upright rings or cups 3, 4, 5, 6 and 7, on the longitudinal center line of the apparatus, successively tangent to one another and hence each braced by the next against displacement through being struck by a ball. Each is also held in place in a way which permits the user to rotate them, for a purpose to be described hereafter. All rings except the lowest are conveniently so held by pegs such as 8, and each surrounds a hole 10, 11, 12 or 13 in the catch board near the front of the ring, so as not to leave any shelf for a ball 14 to hang on. Since the highest ring 7 inclines forwardly away from the back 8' of the box, a brace board 15 notched to fit the ring, is attached to the back, thus serving both as a back brace for the series of rings and to keep balls from lodging behind the ring 7. The front ring 3 is preferably held in place by a block 16 of generally crescent shape, with a flat upper plate 17 of the same shape, sloped backward so as to deliver a ball through the hole 9 in the upper part of the area defined by the ring. The ring 3 can be rotated around this block. A front brace board 18, notched in the middle as at 19 also holds the ring 3. Return openings 20 and 21 are cut through the catch board 1 at the front corners to allow balls which miss the rings to fall through. These openings are of sufficient size not to leave any shelves on which balls could stay.

The box bottom 20 is spaced far enough below the catch board 1 to allow a ball falling through any of the holes to roll freely therebeneath down to an upright ball return board 22 which guides all balls 14 to an outlet opening 23, so that all which have been played will be brought together at one place as shown in Fig. 1, thus facilitating scoring of some games. Side and back curtains 24 and 25 suitably supported by removable poles 26 catch balls which would go over the sides 2.

If it is desired to have audible signals actuated by balls falling into the various cups, upright guide boards 27 and 28, Figs. 4, 5 and 7, can be used between the catch board 1 and the bottom 20 to hold the balls in a path where they will roll under triggers 29 each carrying a tapper 28, each trigger adapted to be raised by a ball running under it and to have the tapper fall back and strike a bell 29A, 29B, 29C, 29D, or 29E as the case may be, each bell preferably ringing a different note so as to give a musical effect and an auditory means of counting the score. Bumpers such as 30, 31 on opposite sides of the passage, of such thickness as just to allow

passage of a ball, give a zig-zag course to the ball, thus slowing its down run so as to cause an appreciable time lag between successive bell signals.

My apparatus as so far described is suitable for games which can be played indoors with golf balls by chip shots, such as with a No. 5 iron, for example. For a putting game a jump board 31 is laid from the top edge of the front 32 of the box to the floor, as shown in Fig. 1, giving an inclined runway. Preferably this jump board has a sharply upwardly inclined top lip 33 to make the ball jump, thereby curving the flight of the ball so that it will fall into one or another of the rings, according to the skill of the player. It is also preferable to finish the bottom edge of the board with a thin lip 31A which will lie practically flush with the floor, or sink into the nap of the carpet, giving a smooth roll for a ball onto the board.

The inner surfaces of the rings 3, 4, 5, 6 and 7 carry for scoring large and distinct markings high enough up to be visible to players, so that by turning all the rings a different sequence of numbers can be exposed, thus adapting my apparatus to be used for playing various games. The developed inner surface of ring 7 is shown in Fig. 2, with score markings thereon, "9," "25," "1" and "300." In Fig. 3 the score markings only are shown for the entire series of five rings, those for each ring being in a horizontal line and indicated by the reference character for the particular ring, the sequence of rings from bottom to top being the same as in Fig. 1. Thus when the rings are arranged to display the numerals of the fourth column of Fig. 3 at the back of each my game is set up for regular golf scoring, the numbers in this instance representing the yardage attained on shots in outdoor golf.

By turning each ring 90° the series of scoring numerals in the next to last column will be displayed, and so on. The balls all roll out on the floor at the same place, and by allowing them to remain there, the number of balls which have been played can always be seen at a glance.

To pack up my game apparatus the back leg is removed, the jump board 31 is lifted off, the curtains 24, 25 and sticks 26 are taken off, the rings 3 to 7 are lifted off their holders, the catch board 1 is removed, the curtains, sticks, rings and jump board are put inside the box, and the catch board is then inverted and laid on top of the brace boards 15 and 19 as a lid for the box.

Having described a preferred embodiment of my game apparatus, together with certain modifications thereof, I wish it to be understood that this description is by way of exemplification, not of limitation, and that my invention is susceptible of modification in details, all within the scope of the appended claim.

I claim:

In a ball game apparatus comprising in combination a plurality of rings of substantial height arranged in longitudinal tangential succession on an inclined board surrounded by walls lower than ring height, holding elements for said rings comprising boards at said front and rear walls, each notched and thereby engaging upper portions of the front and rear rings, respectively, of the series, a supplemental holder for the front ring comprising a lunette of less area than is defined by the ring and over which the ring rotatably fits, said lunette being attached to the inclined board; and having an upper surface inclined oppositely to the board, and a ball escape opening through the board where the lunette surface joins the board surface.

HARTER S. HOOVER.
